PATENTED
NOV 23 1869

3756
31/2

United States Patent Office.

HENRY BERGER, OF NEW YORK, N. Y.

Design No. 3,756, dated November 23, 1869.

DESIGN FOR A CENTRE-PIECE.

The Schedule referred to in these Letters Patent and making part of the same.

To all whom it may concern:

Be it known that I, HENRY BERGER, of the city, county, and State of New York, have invented a new and original Design for Centre-Piece; and I do hereby declare the following to be a full, clear, and exact description thereof, which will enable those skilled in the art to make and use the same, reference being had to the accompanying drawing, forming part of this specification.

The drawing represents a plan of this invention.

This design relates to a centre-piece, composed of a central button, A, which is surrounded by a circular rim, B, ornamented with foliage.

From two opposite sides of this rim, radiate two

ornamental escutcheons, C, which, together with the circular rim B, are surrounded by a festoon, D, giving to the whole centre-piece an oblong shape, of highly ornamental finish.

What I claim as new, and desire to secure by Letters Patent, is—

The design for a centre-piece, as herein shown and described.

This specification signed by me, this 20th day of October, 1869.

HENRY BERGER.
